STOCKING OR SIMILAR ARTICLE

Richard H. Kinley and Frank W. Kinley,
York, Pa.

Application July 7, 1952, Serial No. 20,501

Term of patent 14 years

(Cl. D47—7)

To all whom it may concern:

Be it known that we, Richard H. Kinley and Frank W. Kinley, citizens of the United States, residing at York, Pennsylvania, have invented a new, original, and ornamental Design for a Stocking or Similar Article, of which the following is a specification, reference being had to the accompanying drawing, forming a part hereof.

Fig. 1 is a side view of a flat folded stocking showing our new design, and

Fig. 2 is a fragmentary rear elevation thereof as it appears when worn.

We claim:

The ornamental design for a stocking or similar article, as shown.

RICHARD H. KINLEY.
FRANK W. KINLEY.
